GOLF PRACTICE DEVICE

Mitchell G. Rosengarten, Philadelphia, Pa.

Application June 2, 1934, Serial No. 728,635

9 Claims. (Cl. 273—35)

This invention relates to golf practice devices, and is specially adaptable and advantageous for indoor practice of shots, without danger of injury to walls, furniture, or people. For this purpose, preferably, a missile of innocuous character (as compared with the ordinary golf ball) is used in conjunction with a special device for stopping and registering the shots, like a target. For supporting or "teeing up" the missile, a special device is preferably employed, adapted to assist in directing its flight. Any golf clubs such as used in the regular outdoor golf may be used in practicing with my apparatus.

Various other features and advantages of the invention will appear from the description of one species or form of embodiment hereinafter, and from the drawings. All features hereinafter shown or described are, indeed, of my invention, so far as novel over the prior art.

In the drawings, Fig. I is a general perspective or tilted view of one form of apparatus suitable for the purposes of the invention (including a standard golf club), arranged ready for a shot.

Fig. II is a fragmentary plan view of a base socket such as shown in Fig. I.

Fig. III shows a vertical section through the "target" of Fig. I, taken as indicated by the line and arrows III—III in Fig. I, on a larger scale than Fig. I and with portions of the target-supporting standards broken out.

Fig. IV is a side view of the missile and the tee-clip therefor shown in Fig. I, on a larger scale.

Fig. V is a side view of the missile alone, similar to the view thereof afforded by Fig. IV.

Fig. VI is an edge view of the missile and tee-clip, showing how the missile is held or resiliently gripped by the clip.

Fig. VII is a perspective or tilted view of the tee-clip by itself.

Fig. VIII is a perspective view showing how the target of Fig. I may conveniently be hung on a wall or from any upright surface.

Fig. IX is a view like Fig. VIII showing a different way of hanging the target.

In Fig. I, a missile 10 is shown "teed up" on a supporting device D, which is sighted or directed to properly aim the missile 10 at the stopping and registering device or target T. A golf club C is shown in position behind the missile 10, as if held by a player about to swing the club back over his shoulder for a shot. The target T is shown in a suitable relation to the device D, and one missile 10x is shown lodged in it by a previous shot. Slits x made by other missiles, that have been removed, are also shown.

The form of missile 10 which I at present prefer is a round, flat disc, here shown (Figs. I, IV and V) as very similar to that disclosed in my application Serial No. 648,527, filed December 23, 1932, now U. S. Patent No. 1,980,701. This golf-ball-disc 10 may consist of a circular disc of relatively stiff cardboard, say about 0.025 in. thick. It is shown without any edge notch such as described in my said application, but with a tee-index mark 11 adjacent its periphery (Figs. IV and V), and is printed and colored in imitation of an actual golf-ball having a pitted surface. But this last is quite unessential.

Such a substantially circular disc 10 will correspond fairly well to a real golf ball in behavior, and in flight, when it is properly struck; but the bad effects of improper strokes will generally be exaggerated by it: e. g., a pulled stroke will cause it to deflect sidewise to an exaggerated degree. The deformation of the disc edge by the golf club is also significant: i. e., a perfect shot will simply crush the disc edge to a degree depending on the force of the stroke, while a "topping" shot will produce a notch with one clean-cut edge, etc. The relation of the deformed area to the tee-index mark 11 indicates where and how the disc was struck relative to the tee.

The supporting device D for teeing the disc 10 as shown in Fig. I includes a base 12 and a tee-clip 13. The base 12 may consist of a strip of material (e. g., wood, or rubber) socketed at 14 to receive and hold the clip 13, which, in turn, holds the disc 10. The socket 14 is shown as a keyhole slot, consisting of a round hole 15 drilled through the base strip 12 and a narrow slit 16 sawed or cut from one side of the hole 15 lengthwise of the strip 12. The hole 15 is large enough to receive the lower portion or "butt" of the clip 13 quite freely, while the slit 16, which forms the socket proper, is narrow enough to hold the lower portion or butt of the clip either loosely or snugly, or even tightly.

If preferred, the entrance of the slit 16 from the hole 15 may be V-tapered as at 17 in Fig. II, and the other end of the slit 16 may be made somewhat too narrow for the thickness of the clip 13: this not only facilitates entering the clip 13 in the slit from the hole 15, but allows the clip to be forced in and held just as tightly as each player may desire.

Besides affording a sufficient depth of socket at 14, it is desirable that the base 12 be heavy enough to "stay put" on the floor when properly placed, without requiring to be fastened down. I prefer to make it long enough to allow of its socket slit 55

16 being "aimed" accurately and quickly in the desired direction of flight of the disc 10; which practically requires the socket slit to extend truly lengthwise of the base. A strip of plank 5 30 in. x 6 in. by $\frac{1}{2}$ in. (or less) in thickness answers very well for the base 12.

The tee-clip 13 is shown in Figs. I, IV, VI and VII as a flat strip whose lower end or butt is adapted for insertion in the socket 14 as already 10 described, and whose upper end has resiliently separable jaws or leaves 18, 19 adapted to receive and yieldingly hold the disc 10 between them, as best shown in Figs. IV and VI. As shown in Figs. VI and VII, the jaws and the whole clip 13 15 are alike of laminated construction, consisting throughout of superposed strips 18, 19, preferably of quite stiff, springy cardboard, which may be of about the same character and thickness as the disc 10. These strips 18, 19 are preferably se- 20 cured together at least at their lower or butt ends and where indicated by the dotted line 28 in Figs. IV and VII: i. e., they are free to flex apart only from the line 28 upward. For simplicity in manufacture, they may be cemented or glued to- 25 gether from their lower ends all the way up to the line 28. The strips 18, 19 may be entirely sepa- 30 rate, as shown in Fig. VI; or they may consist of a single long strip doubled flat at the butt end of the clip 13, as indicated in Fig. VII, and suitably secured together at 28, etc. As shown in Figs. IV, VI and VII, the strip 19 projects from under (beyond the end of) the strip 18, to facilitate inserting a disc 10 between the strips as in Figs. IV and VI, as presently to be explained.

35 In teeing up, the player takes a clip 13 in the left hand, with a strip 18 up, and takes a disc 10 in the right hand. Placing the edge of the disc 10 at its tee-index 11 on the projecting end of strip 19, he presses downward, so as to flex strip 40 19 away from strip 18, and then pushes inward so as to insert the disc margin between strips 18 and 19, with index mark 11 about on the center- 45 line of these strips, as shown in Fig. IV. Shifting the grip of his right-hand to include the upper ends of strips 18 and 19 between his thumb and his fore-finger, as well as the corresponding portion of disc 10, he bends over or stoops down and inserts the butt of clip 13 in hole 15 and then shifts it sidewise into slit 16, as shown in Fig. I. 50 Thus the disc 10 is held securely and definitely in the plane of slit 16, at the desired height above base 12, but so loosely that it leaves the clip 13 easily when struck with the club C. Ordinarily, the clip 13 will not be destroyed by a stroke, and 55 may be used over again several times. This is especially so when hole 15 of socket 14 is toward target T, as in Fig. I.

I prefer that the portion of strip 19 exposed under and beyond strip 18 be of a distinctive color, 60 to facilitate placing a disc 10 in the clip as above described: e. g., the outer exposed sides of strips 18, 19 may be red, and their adjacent sides white.

The target device T shown in Fig. I comprises 65 as its principal parts a face or target and registering sheet 22, and a backing or missile-stopping sheet 23. They are mounted upright in super- position, and may ordinarily lie flat against one another.

The facing 22 may be of any material pen- 70 etrable by the missile 10 when driven against it with a force within the range of variation of ordinary playing strokes, such for example as ordinary blotting paper. However, many other (and less expensive) materials or grades of paper may be 75 used, including even newsprint. The facing 22

is here shown as having reference or target marks in the form of concentric circles, whose included areas or intervals and whose surrounding field may in practice be distinctively marked 2, 3, 4, 5, 6, or otherwise suitably distinguished and ranked, as by different colors.

The backing 23 is made practically impene- 10 trable by the missiles 10, and preferably "dead" rather than hard or highly springy; so that missiles penetrating the facing 22 shall not rebound from the backing and fall away, but remain lodged in the facing, as shown at 16x in Fig. I. As shown in Fig. III, such missile discs 10x push the facing 22 and backing 23 apart, at least locally, and hold them apart (until removed), re- 15 maining stuck in the slits which they make and protruding about half the disc diameter through the facing 22. The backing 23 may be of any suitably flexible and yielding material, such as a tex- 20 tile fabric. A cotton fabric of loose texture like cheese-cloth, but woven of rather coarse yarn, answers the purpose very well. It should be stretched or kept under sufficient tension to make it somewhat yieldingly resistant when struck, 25 without rendering it very springy.

If preferred, of course, circles or other reference or target markings may be on the backing 23, instead of on the facing 22, and the facing 22 may be made sufficiently transparent or translucent for them to show through it, as well as penetrable by the missiles 10.

As shown, the backing 23 is in effect a curtain hung from a top rod 24 extending through a wide top hem 25, and tension is applied to it by weight- 35 ing its lower edge. For the size of curtain 23 here- inafter indicated, a brass bottom rod 26 of $\frac{1}{4}$ in. diameter extending throughout a bottom hem 27 affords suitable weighting. The facing sheet 22 is also shown hung from the top rod 24, by means of a couple of hooked clips 28 with spring-closed 40 pivoted jaws 29 gripping the upper margin of said sheet 22. The facing 22 may hang free, with just sufficient tension to keep it flat: in the case of blotting paper, its own weight will afford sufficient loading for this purpose. For a blotter 22 of ordi- 45 nary size such as 24 in. by 19 in., a curtain 23 that is 30 in. long from top rod 24 to bottom rod 26 and 21 in. wide along these rods will be found satisfactory.

In practice, such a target T may be placed 50 some five feet, more or less, from the teed disc 10 at D for the strokes.

As shown in Figs. I and III, the target and backing sheets 22, 23 are hung from the top rod 24 between upright standards 30, 30 fixed in a 55 common (plank) base 31. For this purpose, the upper ends of the standards 30, 30 have eyes 32, 32 in which the rod 24 rests loosely. Longitudinal shifting of rod 24 and accidental disengagement thereof from eyes 32, 32 may both be prevented by knobs 33, 33 screwed on its ends, and one or both removable. To allow of adjusting the height of the target T (according to the character of the club C used and the proper rise of the shots to be made), the standards 30, 30 may be adjust- 60 able in length. For this purpose, they are each composed of telescoping sections 34, 35, the former solid and having the eyes 32, 32, and the latter hollow and snugly but removably socketed in close-fitting holes in blocks 36, 36 fixed on the plank base 31. By making the upper solid sections or rods 34 amply long and bending them slightly near their lower ends, as at 37, 37, they may be made to slide easily enough, but not 65 freely, in the lower tubular sections 35, 35, so as 70 75 75

to maintain themselves at any desired height to which they may be adjusted. As a finish and an additional means of maintaining the adjustment, bored rubber stop discs or washers 38, 38 tightly fitting the rods 34, 34 may be provided, to be themselves adjusted on said rods and rest on the upper ends of the tubes 35, 35.

Modes of use of the apparatus will be obvious from the foregoing description, but may be briefly 10 indicated as follows:

The missiles 10 played from D stick fast in the facing 22 when stopped by backing 23, so that the accuracy of shots may be observed. Competing 15 players may use missiles 10 of different colors, so that their general performances can be compared at the end of an agreed number of shots each. Numerical values may, of course, be assigned to 20 hits in the areas 2, 3, 4, 5, 6, according to their nearness to the center or bull's-eye 2, and scores 25 may be based on them; or, preferably, the numbers 2, 3, 4, 5, 6 may be used directly in scoring, the low score winning as in real golf. In this way, due weight is given to the presumption that each 30 good shot in a game will result in a low total score on the hole on which it is made: e. g., a player who places a shot in the 2 area will presumably make a hole in two, etc.

As shown in Fig. VIII, the target device T of 35 Figs. I and III is hung from a wall, door, or other upright surface W by means of a (flexible) 40 cord or cable 40 secured to the top rod 24 near its ends, and engaged at its own middle with a hook 41 projecting from the wall. The hook 41 may conveniently be removably affixed to the 45 wall W by means of an ordinary rubber sucker cup 42 to which the shank of the hook may be permanently attached. The cord 40 may have an eyelet 43 secured to its middle for engaging the hook 41. Centrally apertured circular discs 44, 44, of stiff 50 fibre cardboard, or the like, may be fitted tight on the ends of the rod 24 (outside the points of attachment of the cord 40), to space the device T away from the wall far enough to keep the missiles 10 from driving the backing 23 against the 55 wall with appreciable force.

Fig. IX shows the target device T of Figs. I and III supported from a wall or other upright surface W without any cord, by means of a pair of hooks 45, 45 individually (and removably) affixed to the 60 wall by the sucker cups 46, 46 to which said hooks are attached. The ends of the hooks 45, 45 have depressions in which the rod 24 rests; and thus the whole device T is held spaced away from the wall W without any need for the discs 44, 44 of Fig. VIII.

While I have here shown and described certain 65 presently preferred forms of construction and types of apparatus embodying my invention, yet it is to be understood that these are not restrictive, but subject to many variations without departure from the spirit of the invention.

Having thus described my invention, I claim:

1. Apparatus for golf practice comprising in combination a missile in the form of a disc adapted to be driven edgewise with a golf club, and a target comprising a sheet penetrable by said disc and a backing therefor yielding relative to said sheet but 5 impenetrable to said disc.

2. Apparatus for golf practice comprising in combination a missile in the form of a disc adapted to be driven edgewise with a golf club, and a target comprising a sheet penetrable by said disc 10 and a separate flexible yieldingly stretched backing sheet impenetrable to said disc.

3. Apparatus for golf practice comprising in combination a missile in the form of a disc adapted to be driven edgewise with a golf club, and a paper 15 sheet penetrable by said disc and a separate textile backing sheet hung against it.

4. Apparatus for golf practice with a missile adapted to be driven with a golf club, said apparatus comprising a sheet penetrable by the missile 20 and a flexible backing limiting penetration of said sheet by the missile.

5. Apparatus for golf practice with a missile adapted to be driven with a golf club, said apparatus comprising a sheet penetrable by the missile 25 and a flexible backing limiting penetration of said sheet by the missile, one of said sheets being marked with target rings numbered from the center outward, and visible from in front of the sheets. 30

6. Apparatus for golf practice with a missile adapted to be driven with a golf club, said apparatus comprising flexible target and backing sheets suspended together but yieldingly separable by 35 flexure, the former penetrable by the missile and the latter impenetrable thereby.

7. Apparatus for golf practice with a missile adapted to be driven with a golf club, said apparatus comprising separate flexible target and 40 backing sheets, of paper and cloth respectively, suspended together but left free to separate when the flexible paper target sheet is penetrated by a missile.

8. Apparatus for golf practice with a missile adapted to be driven with a golf club, said apparatus comprising a supporting bar, a flexible textile curtain suspended from said bar under yielding tension, and a flexible paper target sheet 45 separately and removably hung from said bar in front of said curtain, and free to separate from 50 the curtain when penetrated by a missile.

9. Apparatus for golf practice with a missile adapted to be driven with a golf club, said apparatus comprising a supporting bar, a flexible textile curtain hung from said bar and having its 55 bottom weighted, a flexible paper target sheet in front of said curtain, and hooks attached to the upper edge of said target sheet and hooked over said bar, so that the curtain and target sheet are free to separate when the latter is penetrated 60 by a missile.

MITCHELL G. ROSENGARTEN.
